(57) **CLAIM**

The ornamental design for a padlock, as shown and described.

DESCRIPTION

FIG. 1 is a top perspective view of an embodiment of the padlock;

FIG. 2 is a bottom perspective view of the padlock of FIG. 1;

FIG. 3 is a front view of the padlock of FIG. 1;

FIG. 4 is a rear view of the padlock of FIG. 1;

FIG. 5 is a right side view of the padlock of FIG. 1;

FIG. 6 is a left side view of the padlock of FIG. 1;

FIG. 7 is a top view of the padlock of FIG. 1;

FIG. 8 is a bottom view of the padlock of FIG. 1;

FIG. 9 is a top perspective view of a further embodiment of the padlock;

FIG. 10 is a bottom perspective view of the padlock of FIG. 9;

FIG. 11 is a front view of the padlock of FIG. 9;

FIG. 12 is a rear view of the padlock of FIG. 9;

FIG. 13 is a right side view of the padlock of FIG. 9;

FIG. 14 is a left side view of the padlock of FIG. 9;

FIG. 15 is a top view of the padlock of FIG. 9; and,

FIG. 16 is a bottom view of the padlock of FIG. 9.

The shading lines shown in the drawings represent an approximate three-dimensional contour of the design that form no part of the claimed design.
